(57) **CLAIM**

The ornamental design for an area light fixture as shown and described.

DESCRIPTION

FIG. 1 is a top isometric view of an area light fixture;

FIG. 2 is a bottom isometric view thereof;

FIG. 3 is a front end view thereof;

FIG. 4 is a rear end view thereof;

FIG. 5 is a right side view thereof;

FIG. 6 is a top side view thereof; and,

FIG. 7 is a bottom side view thereof.

The left side view has been omitted as it is a mirror image of the right side view in FIG. 5. The broken lines in the drawings illustrate portions of the article that form no part of the claimed design.

1 Claim, 6 Drawing Sheets
